A. Alexander Thomas

UNITED STATES PATENT OFFICE.

FRANK LAMBERT, OF BROOKLYN, NEW YORK, ASSIGNOR TO THOMSON METER COMPANY, A CORPORATION OF NEW JERSEY.

WRENCH.

1,388,866.

Specification of Letters Patent. Patented Aug. 30, 1921.

Application filed October 22, 1920. Serial No. 418,744.

To all whom it may concern:

Be it known that I, FRANK LAMBERT, a citizen of the United States, and a resident of Brooklyn, county of Kings, and State of New York, have invented a new and Improved Wrench, (Case 5,) of which the following is a full, clear, and exact specification.

My present invention relates to wrenches and its object, broadly stated, is to provide a wrench which is automatically rendered inoperative when the turning power applied to it exceeds a predetermined amount.

The wrench of my invention finds special application in cases where, for certain reasons, it is desirable or necessary that fastening devices (such as bolts, headed screws, nuts and the like) be tightened to a certain degree. As an illustration I may mention the bolts or screws which secure the casing parts of certain water meters where expansion washers or rings are associated with the bolts to permit a separation of the casing parts when the water in the meter freezes. A construction of that kind is set forth in my co-pending application, Serial Number 327,653, filed October 1, 1919. In such a meter, the fastening bolts should not be turned too tight and should, moreover, be tightened as uniformly as possible. With an ordinary wrench that would be difficult, if not impossible, to accomplish, for no two workmen will tighten a bolt alike, much less tighten all the bolts of the same meter to the same extent.

To overcome the foregoing difficulties, I have provided a wrench which automatically becomes inoperative with respect to the bolt or other member acted upon when the turning power applied by the wrench exceeds a predetermined amount. In other words, by the use of my new wrench the proper tightening of a bolt, nut, or other fastening member, is assured.

In the preferred form of my invention, as I have actually employed it, the jaws of the wrench automatically separate into an inoperative position with respect to the member acted upon by the wrench, when this member has been tightened the right amount. Another way of carrying out the idea of my invention is to provide a yieldable connection between the two jaws and the handle, whereby the handle gives way under the application of excessive turning power.

In the drawings, which illustrate two embodiments of my invention,

Figure 1 is a view in elevation of a preferred form of wrench, certain parts of which have been broken away and shown in cross-section for the sake of clearness;

Fig. 2 is a transverse section on line 2—2 of Fig. 1;

Fig. 3 illustrates the application of the wrench to the head of a bolt, or similar fastening member;

Fig. 4 shows the separation of the jaws into an inoperative position when excessive turning power is applied to the wrench;

Fig. 5 shows a modified form of wrench, certain of the parts being broken away and shown in cross-section for the sake of clearness; and

Fig. 6 is a transverse cross-section on line 6—6 of Fig. 5.

Referring to the form shown in Figs. 1 to 4, a suitable handle 1 carries a rod 2 at the outer end of which is fixed the jaw 3. The handle 1 has a screw-threaded opening 4, into which fits the screw-threaded portion 5 of the rod 2, whereby the two parts are rigidly connected together. Broadly speaking, the parts 1 and 2 may be said to constitute the handle of the wrench. On the rod 2 is slidably mounted the jaw 6, which is adapted to coöperate with the fixed jaw 3 to engage the member to be acted upon by the wrench. An adjustable nut 7 is mounted on the screw-threaded portion 5 of the rod 2 at the inner end of the handle 1, and between the nut 7 and the movable jaw 6 is interposed a coil spring 8. The tendency of this spring is to urge the movable jaw 6 toward the fixed jaw 3. Suitable means is provided to limit the movement of the jaw 6 under the action of the spring 8 toward the fixed jaw 3. A simple form of such stop means is shown in the drawings as a sleeve or collar 9, mounted on the rod 2 and interposed between the jaws 3 and 6. To prevent turning of the jaw 6 on the rod 2, there is a key or lug 10 adapted to engage in an axial slot or key-way 11 in the rod 2. For convenience of construction, the lug 10 may be formed integral with the jaw 6, as indicated in Fig. 1, in which case the slot 11 will extend to the end of the rod to permit mounting of the jaw 6. The nut 7 being adjustable permits the regulation of the tension of the spring 8.

The operation of my new wrench will be apparent from the foregoing description and I may briefly explain it as follows: In Fig. 3 the member A is intended to represent dia-
 5 grammatically any suitable form of fastening device,—such as a bolt, screw, nut, or other member adapted to be turned into fastening position. The wrench is applied to this member A in the usual way. Now, as
 10 soon as the member A is sufficiently tightened, the further turning of the wrench will result in the separation of the jaws, as shown in Fig. 4, because the resistance offered by the tightening member A is greater than the
 15 action of the spring 8 on the movable jaw 6. When this occurs, the jaw 6 is pushed away from the jaw 3 against the force of the spring 8 and further turning of the wrench has no effect on the member A. In other
 20 words, the jaws 3 and 6 automatically separate into an inoperative position with respect to the bolt or other member acted upon, when the turning power applied to said member by said wrench exceeds a pre-
 25 determined amount. This amount can be readily calculated beforehand by employing a spring of known tension or resistance. Furthermore, the turnable nut 7 permits the spring to be adjusted to a nicety.
 30 In the modification shown in Figs. 5 and 6, the jaws 12 and 13 are relatively fixed and are pivoted to the handle 14 by means of a pin 15. The handle 14 is at its inner end provided with a forked extension 16 into
 35 which fits the central extension 17 carried by the jaws. The extensions 16 and 17 are provided with aligned openings through which extends the pivot pin 15. The outer ends of the forked extension 16 provide
 40 shoulders 18 against which the jaws rest when the parts are held in normal position by the spring 19. Broadly speaking, the spring 19 constitutes a yieldable connection between the jaws and the handle of the
 45 wrench. This yieldable connection may be mechanically applied in different ways. In the drawings, I have shown the spring 19 housed within the opening 20 of the jaws. The outer end of the opening 20 is closed by
 50 an adjustable set-screw 21, against which bears the outer end of the spring 19. The other end of the spring engages the shoulder 22 of the handle 14. The spring 19 being under tension, its tendency is to swing the
 55 jaws 12 and 13 about the pin 15 (assuming the handle to be a fixed part) until the jaws bear against the stop shoulders 18 of the forked extension 16 of the handle. The adjustable set-screw 21 permits a regulation
 60 of the tension of the spring 19.

Assuming that the wrench shown in Figs. 5 and 6 is applied to a bolt or like member, it will work in the way of an ordinary wrench until the fastening member has been
 65 tightened a predetermined amount. When

that occurs, a further turning of the wrench will result in the handle giving way. That is to say, the jaws 12 and 13 being now a fixed part, the handle 14 will swing about the pin 15 against the action of the spring 19, as indicated in dotted lines 14' in Fig. 5. In that event, if sufficient force is applied, it is obvious that the handle 14 will turn about the pin 15 until the shoulder 22 of the handle abuts against the adjacent end 75 of the jaws. The workman is thus informed that the fastening member to which the wrench is applied has been tightened the proper amount. Of course, the wrench as modified in Figs. 5 and 6 could be turned 80 further, even after the handle has been moved into the position 14', because the shoulder 22 of the handle bears against the inner end of the jaws, but it is assumed that when this occurs the workman will follow 85 given instructions and not attempt to operate upon the fastening member any further. With the wrench shown in Figs. 1 to 4, when the fastening member has been tightened the right amount, further turning of 90 the wrench remains futile, because the jaws simply continue to separate. For this reason the first form of wrench is preferable. But it will be understood that both forms illustrated carry out the underlying idea of 95 my invention,—namely, a wrench having yieldable means whereby the tool is automatically rendered inoperative with respect to the member acted upon when the turning power applied by the wrench to said 100 member exceeds a predetermined amount.

It is immaterial which of the jaws be regarded as the fixed jaw and which one as the movable jaw. For instance, if the handle portion 1 is rigidly connected to the 105 jaw 6, even leaving the spring 8 as it is, the jaw 3 becomes the movable jaw. So it is enough to say that the jaws 3 and 6 are relatively movable.

It will be observed that the jaws of my 110 new wrench automatically resume their normal operative position under action of the spring after they have been rendered temporarily inoperative. This is true of both forms of the invention herein set forth, as 115 will be clearly understood. As far as I am aware, I am the first to devise a wrench possessing this feature.

Although I have herein set forth certain 120 specific forms of my invention, I would have it understood that I do not intend to be limited to the details of structure shown and described, for it is obvious that the basic principle of my invention may be carried out in other ways than those herein described 125 by way of illustration.

What I claim is:

1. A wrench comprising a handle, a pair of relatively slidably jaws carried by said handle for engaging a member to be turned, 130

and spring means for normally holding said jaws relatively fixed, said spring means permitting the jaws to separate into an inoperative position with respect to said member when the turning power applied by the wrench to said member exceeds a predetermined amount, said spring means also causing said jaws to automatically resume their normal operative position after they have 10 been rendered temporarily inoperative.

2. In a wrench, a handle, a jaw rigidly mounted on said handle, a second jaw movably mounted on said handle, a spring for urging the movable jaw toward the fixed 15 jaw, and means for limiting said movement of the second jaw to provide a normal working opening between the jaws, the tension of said spring being such that the second jaw is movable away from the fixed jaw against 20 the action of said spring when the turning power applied by the wrench exceeds a predetermined amount.

3. In a wrench, a handle, a jaw rigidly mounted on said handle, a second jaw movably mounted on said handle, a spring for urging the movable jaw toward the fixed jaw, means for limiting said movement of the second jaw to provide a normal working opening between the jaws, the tension of 25 said spring being such that the second jaw is movable away from the fixed jaw against the action of said spring when the turning power applied by the wrench exceeds a pre-

determined amount, and means for regulating the tension of said spring. 35

4. In a wrench, a handle, a jaw rigidly mounted on said handle, a second jaw mounted to slide on said handle, an abutment on said handle, a spring coiled on said handle between said abutment and said slideable jaw for urging the latter toward said fixed jaw, and means for limiting the movement of the slideable jaw toward the fixed 40 jaw to provide a normal working opening between the jaws, said slideable jaw being 45 movable away from said fixed jaw against the action of said spring when the turning power applied by the wrench exceeds a predetermined amount.

5. In a wrench, a handle, a jaw rigidly mounted on said handle, a second jaw mounted to slide on said handle, a nut on said handle, a spring coiled on said handle between said nut and said slideable jaw for urging the latter toward said fixed jaw, said 50 nut being adjustable to regulate the tension of said spring, and means for limiting the movement of the slideable jaw toward the fixed jaw to provide a normal working opening between the jaws, said slideable jaw 55 being movable away from said fixed jaw against the action of said spring when the turning power applied by the wrench exceeds a predetermined amount. 60

FRANK LAMBERT.
